HYDRAULIC LIFT MECHANISM

Stewart B. McLeod, Detroit, Mich., assignor to
 Motor State Products Company, Ypsilanti,
 Mich., a corporation of Michigan

Application July 16, 1946, Serial No. 345,864

5 Claims. (Cl. 60—52)

This invention relates to a hydraulic lift mechanism or system for raising and lowering or opening and closing tops, covers, closures, and the like, and is adapted particularly, although not exclusively, to the raising and lowering of so-called collapsible tops for vehicle bodies of the convertible type.

One of the objects of the present invention is to provide simplified mechanism of the foregoing character capable of easy application to or installation in a vehicle body, and one in which ample and easily controlled power is provided for the raising or lowering movement of the top.

Another object of the invention is to provide improved mechanism of the foregoing character which is relatively compact and capable of installation in a relatively small space.

A further object of the invention is to provide an improved hydraulic lift mechanism including an operating cylinder and piston structure having a single piston rod, and means for compensating for the difference in volume or space within the cylinder at opposite sides of the piston, said means also compensating for volume changes of the fluid in the system due to the operating pressures and expansion or contraction of the fluid due to temperature variations and permitting manual actuation of the top without using the pump.

Another object of the invention is to provide an improved hydraulic lift mechanism or system having means which permits the system to be filled without the necessity of providing for the external bleeding thereof.

Another object of the invention is to provide improved hydraulic lift mechanism which may include an airtight and upper compensating reservoir and a fluid system connected therewith which together constitute a sealed unit.

Other objects and advantages of this invention will appear in the following description and appended claims, reference being had to the accompanying drawings forming a part of this specification wherein like reference characters designate corresponding parts in the several views.

In said drawings:

Fig. 1 is a fragmentary perspective view of one embodiment of the present invention shown installed in the rear deck compartment of a vehicle body of the convertible type;

Fig. 2 is an enlarged sectional view of the valve mechanism of the present invention, taken substantially along the line 2—2 of Fig. 1, looking in the direction of the arrows;

Fig. 3 is a perspective view of a somewhat modified arrangement of a power unit consisting of an

electric motor, fluid pump, valve mechanism, and associated parts, embodying the present invention; and

Fig. 4 is a view similar to Fig. 2, showing a modified form of valve mechanism embodying the present invention; and

Fig. 5 is a view similar to Fig. 4 showing the valves in their neutral leaking position and also showing another modified form of valve unit embodying the present invention.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring now particularly to Fig. 1, there is shown one adaptation of the present invention. In the present instance the hydraulic lift mechanism or system of the present invention is shown as installed in the rear deck compartment or space 10 of a motor vehicle body of the convertible type in which the top is adapted to be raised and lowered to provide a closed or open body. The mechanism shown may be mounted in any convenient location, such as upon the floor 11 of the rear deck compartment or in a channel member of the vehicle frame, parts thereof being located below and thus concealed by the floor.

In the present embodiment, the lift mechanism is attached or connected to the linkage or frame member, such as the member 12 of the collapsible top for the vehicle body, and comprises a cylinder 13 having a piston 14 mounted upon a single piston rod 15 which is preferably connected with the link 12 through the medium of a substantially U-shaped bracket member 16. The lower end of the cylinder 13 is pivotally mounted for swinging movement at 17 to a base or bracket 18 mounted upon the floor 11. By virtue of the presence of the piston rod 15, it will be understood that when the piston 14 is located at a point in the cylinder midway its opposite ends, the area 19 below the piston is somewhat greater than the area 20 above the piston.

The system includes an oil reservoir 21 and a pump 22 adapted to be driven or operated by means of an electric motor mounted within a casing 23, there being, of course, oil lines or 55 passageways which interconnect the pump and

reservoir with the cylinder 13. Preferably the reservoir is above the valve unit as shown, to make for easier filling. The motor 23 is of the reversible type capable of being driven in either a clockwise or a counterclockwise direction so that the pump 22 may likewise be driven in either direction. The reservoir 21 communicates through a pipe line or tube 24 with a compensating or shuttle valve unit shown as a whole at 25, see particularly Fig. 2. The oil pump 22 is connected by means of a pipe line 26 to the left side of the valve 25 through the medium of a T-shaped coupling 27 to which is attached a pipe line 28 which extends through a base plate 29 mounted on the floor 11 and is connected to another pipe line 30 which extends to and is tapped at 31 into the cap or upper end 13a of the cylinder.

A pipe line 33 extends from the pump 22 to a T-coupling 34, similar to coupling 27, and is tapped into the right side of the valve 25. Another pipe line 35 extends from the T-coupling through an opening in the floor plate 29 and is connected to a pipe line 36 which is tapped into or connected at 37 to the lower cap member or closure 13b of the cylinder.

The instrument panel 8 of the vehicle supports an electric switch 40 controlled by a pull rod 41. This switch is electrically connected by wiring or cable 42 to a solenoid 43 mounted upon the motor casing.

As described above, my improved hydraulic lift mechanism or system includes means for connection to a frame member or linkage at one side only of a collapsible top. It will be understood that if it is desirable to connect the hydraulic mechanism to a similar frame member or linkage at the opposite side of the top, an additional cylinder 130 is provided. The construction of the cylinder 130, its piston, piston rod, mounting means and the means for attaching the piston rod to the linkage of the top is similar to that above described. As shown in Fig. 1, the pipe line 28 extends through an upright supporting bracket 45 and is connected to a transversely extending pipe line 46 which passes through brackets 47 and 48 attached to a body frame member and to the floor respectively, and is connected to a pipe line 49 which extends to and is connected with the upper end of the cylinder 130. The pipe line 35 from the opposite end or side of the valve structure 25 has a branch connection through the bracket 45 with a transversely extending pipe line 50, which pipe line extends through bracket 47 and plate 48 and is connected with a pipe line 51 which is tapped into the lower end or head 130b of the cylinder by means of a tap or connection 52. It will be understood that all or portions of the pipe line referred to may be in the form of flexible hose or conduit, thus permitting freedom of movement of the cylinders 13 and 130. Thus, when the motor 23 and pump 22 are driven in a clockwise direction, oil passes under pressure through the lines 26, 28 and 30 to the upper end of the cylinder 13 and at the same time through the lines 46 and 49 to the upper end of the cylinder 130. The pressure of the oil or other fluid in the system when the motor and pump are being driven in a clockwise direction forces the pistons in the respective cylinders 13 and 130 downwardly to move the links or top frame members or bows downwardly toward the floor 11 to collapse the top (not shown).

Referring now particularly to Fig. 2, and with high pressure being applied to the chambers above the pistons in the cylinders 13 and 130, the parts of the compensating or shuttle valve unit 25 are in the positions shown in this figure.

The valve structure 25 has a body portion 60 which, as shown merely by way of example, is of substantially T-shape having a transverse port or passageway 61 and a connecting longitudinal passageway 62. It will be understood, however, that the body portion may be of any desired shape. Valve seats 63 and 64 are formed in the body at opposite ends of the passageway or valve bore 62. The body is hollowed out at its opposite longitudinal end portions to provide sockets or chambers 65 and 66. These chambers are internally threaded at 65a and 66a to receive and support threaded coupling nuts 67 and 68. Pipe lines 26 and 35 are connected with the couplings 67 and 68, respectively.

The shuttle valve assembly for each of the chambers 65 and 66 and the passageway 62 is identical. As shown, the assembly at the left of Fig. 2 comprises a poppet or disk valve 69 mounted upon a stem 70 and held against an abutment by spring 74. The valve 69 has one or more openings or passages 69a therethrough. The valve stem is supported in position by means of a compression spring 71 whose inner end engages the head on stem 70 and also engages the central portion of the valve 69. The outer end of spring 71 seats against the inner face of member 67 and is maintained in position by means of a series of fingers or projections 72 on said member.

The stem 70 also carries a relatively smaller disk valve or excess pressure relief valve 73 which is normally urged toward the poppet valve 69 to close the openings or ports 69a in the valve 69 by means of a compression coil spring 74, having its outer end seated against the valve 73 and its inner end against a washer 75 adjustably held in position by a nut 76.

The valve assembly at the right of Fig. 2 comprises parts corresponding to those of the valve assembly at the left of this figure, namely, a disk valve 79 having one or more holes or openings 79a therethrough. The valve is mounted upon a stem 80 and is supported in position by a compression spring 81 whose outer end engages and grips the head on stem 80 and also engages the central portion of the valve 79. The inner end of the spring 81 seats against the inner face of member 68 and is maintained in position by means of a series of fingers or projections 82 on said member.

The stem 80 also carries a relatively smaller excess pressure relief disk valve 83 which, as shown herein, is held against the poppet valve 79 to close the openings 79a formed therein, by means of a compression coil spring 84 having its outer end seated against the valve 83 and its inner end against a washer 85 adjustably held in position upon the stem 80 by a nut 86.

The filling and bleeding of the system may be accomplished substantially as follows:

The system is filled through the reservoir 21 by pouring fluid into the reservoir and running the pump 22 in one direction thereby sucking the fluid from the reservoir until the piston 14 of cylinder 13 has reached the end of its stroke and no more fluid can be added. The pump is then operated in the opposite direction and the reser-

voir is filled as necessary and fluid sucked from the reservoir and the other end of the cylinder until the piston has reached the end of its stroke in the opposite direction.

To completely bleed the system the pump is first operated in one direction and then in the opposite direction several times until all of the air is completely forced out through the relief poppet valves 73 and 83.

The operation of the mechanism heretofore described is substantially as follows:

The pull rod 41 on the instrument panel is actuated to operate the electric switch 40 and the solenoid 43 to run the motor and drive the pump 22 in a counterclockwise direction. When the pump is thus driven or run in a counterclockwise direction, the fluid is drawn from the upper end of the cylinder 13 and forced into the lower end thereof. However, as the volume or capacity of the upper end of the cylinder is less than that of the lower end due to the presence therein of the piston rod 15, a suction is created in line 26 opening the poppet valve or flapper 69 and allowing fluid to be drawn from the reservoir 21 past valve 68 into the line 26 and hence to the lower end of the cylinder to compensate for this difference. The flapper or poppet valve 79, of course, is closed under the influence of its spring 81 and the pump pressure in coupling 34. When the line pressure of the lower end builds up to a predetermined high pressure, the relief poppet 83 starts to open gradually until at any predetermined pressure such, for example, as 125 pounds per square inch, it has opened sufficiently to by-pass enough fluid through the holes 79a in the flapper 79 on the pressure side of the pump, around the open flapper or poppet valve 69, to the suction side of the pump 22 so that no further pressure can be built up and the line pressure will remain constant and never exceed the predetermined pressure setting.

When the pump 22 is operated in a clockwise direction the fluid is drawn from the lower end of the cylinder 13 and forced into the upper end thereof. However, as the volume or capacity of the upper end of the cylinder is less than that of the lower end due to displacement by the piston rod, an excess or surplus of fluid is left in the lower end of the cylinder as the piston 14 starts to move downward under the pressure of the fluid built up in line 26. The flapper valve 69 remains closed under this pressure. This excess fluid in the lower end of the cylinder is then put under compression by the movement downward of the piston 14 and pressure is also built up in the lower end causing the flapper valve 79 to also remain closed as a result of the pressure applied to the upper end and the consequent movement of the piston. These pressures both increase until relief poppet 73 starts to open according to its predetermined setting and allows this excess oil to by-pass through holes 69a in the flapper valve 69 and into the reservoir 21. When all of this excess fluid has by-passed into the reservoir, then line 35 becomes the suction side of the pump and the by-pass at pop off pressure (125 pounds per square inch) is as before, from the line 26 at the pressure side through holes 69a in the poppet valve or flapper 69 around the open flapper 79 to the line 35 at the suction side. Thus Figure 2 shows this condition after this excess liquid has been by-passed into the reservoir, and relief valve 73 remains open and the relative suction in coupling 34 has opened

valve 79. Thus in this form of the invention with the main valves independent, the relief valves 73 and 83 are essential to the operation, as it will be apparent that the piston could not move if they were not present and there were no substantial leakage.

The foregoing description relates to the operation of the device in connection with a single cylinder 13. It will be understood that when a second cylinder, namely, the cylinder 130, is employed, the interconnecting lines 46, 50, etc., as described above, function with their associated lines 26, 33, etc., and in connection with cylinder 13 to actuate the pistons in both cylinders simultaneously.

It is to be understood that the reservoir 21 is used only as a compensatory and also a reserve supply reservoir. This reservoir compensates for the difference in volume between the upper end 20 of the cylinder (or cylinders) and the lower end thereof due to the presence of and therefore volume or space occupied by, the piston rod 15. In other words, without the reservoir 21, the volume of oil in the lower end of the cylinder would all have to be forced into the smaller space or volume at the upper end of the cylinder. This, of course, would be impossible and the result would be a locking or binding of the oil pump and the piston at some point in the stroke. Moreover, due to the space occupied by the piston 15, there is not sufficient oil in the upper end of the cylinder 13 to completely fill the lower end thereof. However, the reservoir 21 also provides means for compensating for volume changes of the oil 35 due to the operating pressure and to the expansion or contraction of said oil due to any temperature variation. In addition, the compensating reservoir permits filling of the system without the necessity of external bleeding, that is, the 40 pressure balance valve, through the medium of the reservoir, is self-bleeding when the system is filled.

By virtue of the fact that the reservoir 21 is merely a compensating reservoir for the slight 45 changes in volume, and because of the fact that a slight vacuum or a few pounds of pressure in the reservoir would make no difference to the operation of the system, due to the presence of the pressure balance valve, the reservoir can be 50 made airtight and thus the whole fluid system becomes a wholly sealed unit.

Referring now particularly to Fig. 3 of the drawings, there is shown a somewhat modified and preferred arrangement of the power unit constituting the present invention. In this form of the invention the electric motor 90 and the gear pump 91 for the fluid are arranged in tandem and preferably in a horizontal plane. The valve unit 25 is preferably attached to the end of the pump 55 casing or housing. The entire unit is adapted to be fastened to a supporting surface by means of bolts or the like 92. Mounted upon the casing of the electric motor 90 are a pair of solenoids 93 and 94, respectively, these solenoids being arranged in tandem. Electric current is supplied to the solenoids 93 and 94 by a cable 95 leading from the vehicle battery. Suitable electric conduit bands, straps, or members 96 and 97 connect the source of power to the solenoids and to the electric motor. The switch 40, shown in Fig. 1, is connected with the solenoids 93 and 94 through the medium of the wires or cables 42, seen also in Fig. 1.

In other respects, the present arrangement of

power unit is similar to that of Fig. 1, there being a pipe line 24 leading to the upper oil or other fluid reservoir 21. Pipe lines 28 and 35, corresponding to similar lines shown in Fig. 1, lead from opposite ends of the valve casing or unit 25.

By virtue of combining the electric motor, the gear pump, and the valve unit in a single unit in tandem relation, as shown in Fig. 3, a smaller space within the vehicle will be required to accommodate this unit of the hydraulic lift mechanism embodying the present invention and installation, mounting, and service are easier, and the cost is reduced.

The valve mechanism shown in Fig. 4 is substantially like that of Fig. 2 except that the poppet or disk-like valves 69 and 78 are controlled or actuated by mechanical means as well as by fluid pressure in the system. That is to say, when one poppet is held against its seat by fluid pressure, the other poppet is held off its seat mechanically. With the parts in the positions shown in Fig. 4, fluid pressure in the system is holding the valve 69 on its seat 63 whereas the valve 78 is simultaneously held off its seat 64 by mechanical means. As shown herein, merely by way of example, the valve stems 70 and 80 have inward opposed extensions 70a and 80a, respectively, which project inwardly beyond the inner faces of the spring adjusting nuts 76 and 86 and abut or engage one another. Thus, the valve stem 70, 70a mechanically holds the valve 78 off its seat. With the parts in the reverse position or toward the left of Fig. 4, with the valve 78 against its seat 64, the valve stem portions 70a, 80a will mechanically maintain the valve 69 unseated or off its seat 63. As will be seen from Fig. 4, and since the two valve stems 70 and 80 are long enough to hold one valve off its seat when the other is closed, it will be apparent that when the valve unit itself (the two valves 69 and 78 and their stems 70 and 80) is held in its normal or inoperative central position by the identical light centering springs 71 and 81, the valves will be slightly off their seats and will thus permit a small by-pass leakage through the valve bore. This feature is valuable since it permits a direct manual operation of the top when the pump is inoperative, as when the electric motor cannot be turned on or the like. For example, if the electric motor is energized through the ignition switch, the top can be raised if the owner is away with the ignition key.

As will be apparent, the valve units shown in Figs. 1 and 4 and having two valve rods, one for each end of the valve bore, will permit individual adjustment or removal and insertion of the two valves and their stems.

If desired, a single common valve stem may be employed for both of the valves 69 and 78, which if used, would supplant separate valve stems 70, 70a and 80, 80a. In that event, a single spring between the relief poppets 78 and 83 would take the place of the separate springs 74 and 84. It will be understood that if a single valve stem were used, it would be of the proper length so that when one of the poppet valves was seated, the other valve would be off its seat and here also there will be the by-pass leakage in inoperative position to permit direct manual operation of the top and consequently of the direct connected piston motor. As will be apparent, both here and in the form of Fig. 4, the centering springs will aid in holding the valves slightly off their seats to permit slow manual operation since the valves will not be closed until there is an appreciable

pressure and rate of fluid flow to close the high pressure side valve.

This single valve stem form of the valve unit is shown in Fig. 5, which is identical with and has reference characters similar to Fig. 4, except for the single spring 74' for the relief valves, the single valve stem 70', and the omission of parts 76, 86, and separate abutting stem parts 70a and 80a. It will also be seen that Fig. 5 shows both the valves 69 and 78 held off their seats in their neutral leaking position.

When the valve mechanism of Fig. 4 is employed, the filling and bleeding of the system would be accomplished substantially as follows:

15 The system is filled through the reservoir 21 by pouring fluid into the reservoir and running the pump 22 in one direction thereby sucking fluid from the reservoir until the piston 14 has reached the end of its stroke and no more fluid 20 can be added. The pump 22 is then run in the opposite direction with the reservoir kept full and the oil or other fluid is sucked from the reservoir and the oil end of the cylinder 13 until the piston has reached the end of its stroke in the 25 opposite direction.

Bleeding may be accomplished in two ways in the present system.

The pump is first operated several times, first in one direction and then in the other direction. 30 When the pressure poppet or flapper valve closes, the other poppet is mechanically held open by the contacting stems 70a and 80a so that the supply side of the valve mechanism or line is always open to the reservoir 21 and to atmosphere. 35 Accordingly, any air in the system is free to escape from the side not under pressure during the operation of the unit and the movement of the piston.

Additional bleeding is accomplished through 40 the relief poppets 78 and 83 which open gradually under pressure and allow the air to be forced out.

The operation of the system when embodying the valve mechanism of Fig. 4 or of the common 45 valve stem form is substantially as follows:

When the pump 22 is run or operated in a counterclockwise direction, the fluid is drawn from the upper end of the cylinder 13 and forced into the lower end thereof. Thus pressure in line 28 closes the poppet valve 78 and opens valve 69 as the flow increases. The reservoir is then mechanically placed in communication with the upper end of the cylinder line so that the needed extra fluid due to the piston rod 50 displacement in the upper end of the cylinder may be directly drawn from the reservoir. The relief poppet valve 83 functions in exactly the 55 same manner as in the mechanism of Fig. 2.

When the pump 22 is operated in a clockwise 60 direction the fluid is drawn from the lower end of the cylinder 13 and forced into the upper end thereof. Thus pressure in line 28 similarly closes the poppet or flapper valve 69 and opens the valve 78. The reservoir 21 is then mechanically communicated with the lower end of the cylinder line so that the excess fluid in the bottom of the cylinder 13, due to the displacement 65 of the piston rod in the upper end of the cylinder, is free to flow into the reservoir during the operation of the unit and the movement of the piston 14.

The relief poppet 78 functions in exactly the same manner as in Fig. 2.

Thus it will be apparent that in these other

forms of the invention, in which the main valves 69 and 79 are not independent but interact so that when one is closed it holds the other off its seat, the relief valves 73 and 83, while not essential to operation as in the first form, are highly desirable to not only limit excess pressures in the motor, as from thick oil on a cold morning and to permit the use of an excess powered electric motor and pump, but, more important, to provide a safety feature whereby the rate of motion of the convertible top and particularly the force pushing it are limited so that it is not dangerous (as to children) and, in fact, may be stopped by hand if the switch cannot be reached. Obviously, these advantages may also be realized in the first form.

It is to be understood that the operation is the same as above described when two cylinders 13 and 130 are employed.

It will be understood that the hydraulic power system embodying the present invention can, of course, be operated from any convenient form of power other than the electric motor described herein. If the source of power could not conveniently be reversed, a valve could be installed in the pressure and suction lines in the vicinity of the pump 22 to reverse the flow of fluid in these lines by means of a moving plunger instead of by means of reversing the pump itself.

I claim:

1. In a hydraulic lift mechanism for raising or lowering a convertible automobile top or the like, in combination, a reversible electric motor, a liquid pump rotated in either direction thereby, a double acting cylinder and piston motor to raise or lower said top and having a piston rod at one end only so that unequal volumes are displaced at the two ends of the cylinder, two conduits connected to carry liquid from opposite sides of the pump to opposite sides of the piston, a compensating and replenishing valve unit comprising means defining a valve bore connected between said conduits, a liquid reservoir connected to the intermediate portion of said bore and forming a sealed system with said conduits, the pump, the valve, and the cylinder, said bore having at each end a valve seat and a cooperating valve member to be selectively seated by liquid flow from the pump outlet, rod means between said valve members and having a length slightly greater than the spacing between said valve seats, and centering spring means normally or in inoperative position holding said two valve members slightly off their seats to permit manual lifting of the top and consequent actuation of the piston.

2. In a convertible automobile top mechanism, a wholly sealed hydraulic actuating mechanism comprising a double acting piston motor having only a single piston rod, a reversible liquid pump, a reversible electric motor driving said pump, conduits between said pump and motor to operate it in either direction, a liquid reservoir, and a shuttle valve unit including movable valve means actuated automatically and only by the liquid flow and pressures for selectively connecting said reservoir to the then low pressure conduit for either direction of piston motion, said valve unit having means therein, including centering spring means for its said valve means, to always automatically provide, upon non-operation of said pump, a by-pass leakage passage through said valve unit only in normal, inoperative, centered valve means position to permit slow direct manual

operation of the top and motor by liquid flow through said by-pass leakage passage, and said movable valve means including, as a part thereof and moving and cooperating therewith, resiliently biased excess pressure relief valve means to limit the pressure in either end of said piston motor in either direction of its travel by venting it to the other end of the cylinder and to the reservoir to thus permit the use of an excess powered electric motor and pump with safety to careless passengers.

3. In a mechanism for convertible automobile tops or the like, a hydraulic actuating system comprising a double acting piston motor having a single piston rod to directly raise or lower said top, a reversible electric motor, a liquid pump means connected to operate said motor, a reversing electric switch as the sole control for said electric motor and pump, a compensating shuttle valve unit operated automatically and only by the pressures due to liquid flow and connected across said pump connections, a liquid reservoir positioned above said valve unit and connected to said valve unit to be selectively communicated with the then low pressure side of the pump during pump operation, said shuttle valve unit including resilient valve centering means and cooperating means to provide upon non-operation of the pump means a by-pass leakage through said valve unit in its centered inoperative position to permit direct and slow manual actuation of the top and its motor piston.

4. In a mechanism for convertible automobile tops or the like, an hydraulic actuating system comprising a double acting piston motor having a single piston rod to directly raise or lower the top, reversible liquid pump means connected to operate said motor, a liquid reservoir, and a motor volume change compensating shuttle valve unit comprising means defining a valve bore connected across the pump liquid connections, a connection from the reservoir to the intermediate portion of said bore, an outwardly facing valve seat at each end of said bore, a pair of coaxial and normally abutting valve rods in said bore, each carrying at its outer end a disk valve mounted thereon to be movable back and forth therewith and to be selectively closed against the valve seat only by the pressure from the then high pressure side of the pump so that it acts directly on its valve rod and through the abutting valve rods to push the other disk valve toward open position and to lift it off its seat, the length of said abutting rods and the spacing between said disk valves being greater than the distance between said valve seats, so that when said rods and their valves are centered both valves are off their seats to provide a through or by-pass leakage passage and a centering spring in each end of the valve bore acting against each disk valve to automatically return them to and normally hold them in centered positions off their seats during non-operation of said pump means or low rates of liquid flow and pressures to thus permit slow manual operation of said top and said piston motor by liquid flow through said by-pass leakage passage.

5. In a raisable or lowerable automobile convertible top mechanism or the like, an hydraulic mechanism comprising a double acting piston motor having only a single piston rod, a reversible flow liquid pump, a reversible electric motor driving said pump, conduits between said pump and

motor to operate it in either direction in accordance with the direction of rotation of said electric motor, a compensating liquid reservoir, and a compensating valve unit for selectively connecting said reservoir to the then low pressure conduit for either direction of piston motion to compensate for the difference in volumes due to the single piston rod, said unit including two independent and unconnected oppositely acting valves resiliently biased to their closed positions and 10

5 actuated automatically and only by the pressure differences produced by liquid flow, each of said valves having a valve opening therethrough with a valve seat thereon and a resiliently biased and oppositely opening relief valve cooperating with each of said openings and seats to permit said compensation and to limit the high pressure in said piston motor to a predetermined value for safe operation.

STEWART B. MCLEOD.
